CLAIM

The ornamental design for a bottle, as shown and described.

DESCRIPTION

FIG. 1 is a front perspective view of a bottle showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is an exploded front perspective view thereof; and, FIG. 9 is a front perspective view of the bottle of FIG. 1 with a top cork in an exploded view above.

The broken lines in FIGS. 7 and 9 are for illustrative purposes only, and form no part of the claimed design.
